FREQUENCY CONVERTER

Joseph L. Roemisch, Montclair, N. J., assignor to
 Western Electric Company, Incorporated, New
 York, N. Y., a corporation of New York

Application February 7, 1942, Serial No. 429,932

3 Claims. (Cl. 250—36)

This invention relates to frequency converters and especially to what has frequently been denominated a self-synchronizing system wherein a wave of a given frequency from a coercing oscillator coerces an oscillator to cause it to operate in locked synchronism with the coercing oscillator and to generate a wave having a frequency bearing a commensurable relation to the frequency of the coercing wave.

The above statement as to the necessary "commensurable" frequency relation between the two waves concerned was used to indicate the possible breadth and generality of the invention. That is, although the invention may be used, and perhaps could be used most effectively, to either step up or step down the frequency of the given coercing wave to a frequency which is an integral harmonic or subharmonic thereof, the principle may be equally well used to achieve a coincidence of the two frequencies, or to achieve any one of an infinitude of relationships where there is not an integral harmonic relationship between the two frequencies, but which nevertheless come within the definition of a "commensurable relation" therebetween, which means that the frequencies concerned have an integral common divisor.

More particularly, the invention comprises a self-synchronizing system as above in which the coerced oscillator is of the negative transconductance tube type and especially one in which there is a strategically positioned and electrically valued impedance adapted to make said oscillator more easily coercible without detriment to other functions which make the measure of an efficient and accurate self-synchronizing system.

It is an object of the invention to achieve self-synchronization by the use of a negative transconductance tube oscillator as the coerced oscillator.

It is a more particular object of the invention, consistently with the above brief characterization, to so electrically condition a negative transconductance tube oscillator to make it more easily coercible consistently with the satisfaction of other desirable conditions inherent in the operation of efficient self-synchronizing systems.

It is a further object of the invention to provide an oscillator that is readily coercible over a wide range of the coercing frequency and furnishing an output signal of essentially sinusoidal wave shape.

It is a still further object of the invention to provide an oscillator in itself having a high degree of stability and purity of output wave shape

and yet being capable of a high degree of coercion by a coercive signal much smaller in magnitude than the coerced signal.

It is a feature of the invention that the circuit arrangement is limited, as regards coercion, by the use of certain circuit constants for inductance and capacitance to coercion at only the approximate antiresonant frequency of the inductance-capacitance circuit.

The above objects can only be realized by a circuit utilizing a discharge tube containing elements that will permit its ready functioning as a negative transconductance oscillator of the direct coupled type and conditioned by means of a suitable resistor R, to be described, in the anode lead of the discharge tube.

The organization of the invention is an alternative in its class of self-synchronizing systems. For instance it achieves in general the same ultimate result, and in somewhat the same manner, as the organization of the same class in which a controlled multivibrator is used. However, the present organization has an advantage thereover, in that it requires the use of only one electric discharge tube as against two tubes required by a multivibrator. There are other advantages over this and other alternatives in the same class, some of which are specific per se to the particular type of coerced oscillator used, namely the negative transconductance tube oscillator, besides others which illustrate the particular adaptability of this type of coerced oscillator in the self-synchronizing organization, but which are not suggested from the characteristics of this type of oscillator when used as an independent source of oscillations. It is believed that applicant is the first to have appreciated these advantages and to have discovered a means for realizing them in a practical way. The advantages here in contemplation will more appropriately be pointed out in connection with the detailed description that follows.

A more full description of the invention appears hereinafter in connection with the drawing wherein:

Fig. 1 illustrates, in large part diagrammatically, a specific embodiment of the invention; and

Figs. 2 and 3 similarly represent alternative species of the invention. The three species are identical except for the specific means for introducing the coercing wave.

Referring to Fig. 1 of the drawing, the coercing source is shown diagrammatically at 1. The remaining part of the circuit, that is, the

coerced oscillator, is, largely because of negative transconductance tube 4, a negative transconductance tube oscillator, generally of the type disclosed in United States patent to Herold 2,217,748, October 15, 1940, and more specifically similar to the arrangement described in Fig. 8a of Herold's paper beginning in page 1201 of the Proceedings of the Institute of Radio Engineers for October, 1935, although the present circuit has features of significance which differentiate the oscillator from that of Herold.

A negative transconductance tube, as exemplified herein, and in the Herold references, is a tube in the operation of which an increase of potential on the control electrode results in a corresponding increase of potential on the anode, exactly the reverse of the operation of a conventional tube in which an increase of control electrode potential causes an increase of current in the anode circuit resulting in an increased drop and hence a decrease of the anode potential. As stated in a complementary way, a negative transconductance tube is a tube in the operation of which an increase of potential on the control electrode results in a corresponding decrease, instead of an increase, in the anode current. In the instant case, and the parallel with the above Herold disclosures should be at once apparent, an increase of potential on the control grid 5 with respect to the cathode 6 results in an increase of potential on the anode 7. Usually, as in the instant case, a pentode tube is used, comprising, additionally to the above, the auxiliary anode 8 and the synchronizing or injection grid 9. The grid 9 is not of great importance in the circuit of this figure, but the grid 7 here referred to as the "anode" and the suppressor grid 5 here referred to as the "control grid" are of great importance as being essential in the negative transconductance tube. In particular the potential on the anode 7 should be positive and relatively large as compared with the positive potential on auxiliary anode 8, the potential on the control grid 5 being negative and small. The potentials indicated in Fig. 1 for electrodes 5, 7 and 8 would be very satisfactory. Any of pentode tubes 6SJ7, 6SK7, 6D6, 6C6, 57, and 58, together with others, would be satisfactory. The potential for the anode 7 and auxiliary anode 8 are derived from direct potential source 10, the indicated potential of 105 volts for the anode being intended to be with reference to the cathode, that is, be the potential of the source 10 as a whole instead of only that portion of it between the auxiliary anode 8 and the anode. The same statement is applicable to the Figs. 2 and 3 modifications since, as is pointed out in the brief description of the figure, the species are identical except for the specific means for introducing the coercing wave. Obviously alternative means, a choice of which are well known in the art, could be used to obtain these potentials. The negative potential for the control grid is derived from source 12 through resistance 11. The supply current for the anode 7 is fed through resonant frequency determining circuit 13 and resistor R.

Resistor R is the most important feature of the system of the invention, since it is the element which enables the negative transconductance tube oscillator, the other elements of which have long been known, to be coerced by oscillator 1 with results greatly superior in degree of synchronizing control to that of any previously known oscillator or frequency generator whose

frequency is determined in some way by a resonant circuit.

The portion of the circuit of the coerced oscillator, as so far described, because of the included negative transconductance tube 4, well lends itself to the production of self-sustained oscillations. The coincidence of potential phase on the control grid or electrode 5 and anode 7 in fact makes it more easy to evolve a self-contained oscillator from the circuit than from the corresponding elements of the conventional oscillator tube, since a feedback in proper phase from the anode 7 to control electrode 5 may be achieved by a direct connection therebetween, although in this instance a capacitor 14 having a low reactance for the frequency of the LC circuit 13 is used to block off from control grid 5 the direct current potential applied to anode 7 since control grid 5 must be negatively charged. The negative transconductance tube oscillator is completed by adding said connection including the capacitor 14 between said elements 7 and 5 and the resonant tuned circuit 13, which is effectively in circuit between said anode 7 and the cathode 6 and is adapted to determine the characteristic frequency of said oscillator. Because of the negative transconductance tube arrangement, as above explained, oscillations may be generated, by virtue of the peculiar characteristics of the tube together with the use of the frequency determining circuit 13, having a high degree of inherent stability and in addition a very low degree of harmonic content.

The self-synchronizing system of Fig. 1 is made complete by the connection of the coercing oscillator 1 as shown to the coerced negative transconductance tube oscillator. As shown, this coupling is to the anode of the coerced oscillator. However, the coupling could be made to other elements of the coerced oscillator tube without detriment to the operation of the principle of the invention. In fact, the circuit of Fig. 2, to be described later, illustrates an alternative connection. No specific means is shown for taking off power from the coerced, that is, controlled, oscillator. However, this is not important since the power take-off connection may be made almost impartially to the various tube elements. Generally such power is taken off across resistor R. It is noted that in the above referred to Herold Patent 2,217,748, October 15, 1940, an additional anode, coupled to the oscillator electrodes proper only through the electron stream is used. This expedient could equally well be used in the circuit of applicant's invention.

The operation of a negative transconductance tube oscillator may be described briefly as follows: As above described the distinguishing characteristic of a negative transconductance tube, and the operation to be expected in the present instance, is that the anode current decreases when the control grid potential becomes less negative, or more positive. Assuming that a pulse occurs by closure of the anode supply circuit or by any other circuit disturbance, a potential will result across resistance R and tuned circuit 13. This potential will affect the potential of the control grid through the coupling capacitor 14 and cause it to be less negative (assuming a positive pulse). Negative resistance will thus be created and the anode current will decrease until it can decrease no more at which point the tube will discharge the electric charge represented by the capacitance in the tuned circuit 13 and another sequence will start. The fre-

quency of the succession of operation will be the characteristic frequency of the oscillator, this frequency being determined by the time constant or period of tuned circuit 13. If a potential is impressed from source 1 having precisely the frequency and phase of the wave generated by the oscillator, there will obviously be no interaction. However, a deviation from frequency coincidence will result in the introduction of a new, coercing, force. It is not necessary to postulate a relative change of the oscillation frequency either upwardly or downwardly from the coercing frequency nor is it necessary to explain the precise mechanics of the operation. It is true, however, that the coercing force or potential is always in proper phase to aid the negative resistance function that causes control.

The grid 9, while not used in the Fig. 1 species directly in the coercing action, nor is needed as a part of the negative transconductance tube oscillator per se, does provide a means for control, and this will be illustrated in Fig. 2. If this grid should become negatively charged, obviously no electrons could pass it and the circuit could not oscillate at all. If it became positive, more electrons could flow to the anode and control grid, this resulting in a more favorable condition and a lower negative resistance. Therefore a wave applied to said grid 9 does tend to influence the circuit by changing the negative resistance of the tube. If the negative resistance is lowered, the circuit will oscillate more readily and vice versa.

Now, if a resistor, like resistor R, is inserted in the anode lead, the circuit tends to become a relaxation oscillator, in fact would become a relaxation oscillator were it not for the high impedance of the LC circuit 13. If the resistance of said resistor is increased too much, the circuit will cease oscillating. The point of maximum coercion is just before oscillations cease. This points to one of the necessary conditions for efficient operation to be discussed a little later.

As has been stated, this resistor R is principally responsible for the unique results achieved in applicant's self-synchronizing combination. The use of resistor R and its adjustment to the maximum value that will still permit the normal oscillation of the circuit at a frequency determined by circuit 13 permits the oscillator arrangement to be coerced by a coercing signal at the fundamental, subharmonic, harmonic, etc. of the coercing signal frequency to a degree far greater than that achieved by any other system wherein the coerced oscillator is one whose frequency is determined, substantially, by the resonant frequency of a circuit connected or associated therewith.

In addition this arrangement permits the coercion of an oscillator having a signal output of relatively large amplitude by a coercing signal having an amplitude much smaller than that of the coerced oscillator. All previous systems wherein the frequency of the coerced oscillator is determined by the resonant frequency of an associated coil and condenser require the coerced oscillator signal amplitude to be considerably less than that of the coercing oscillator. This results in a peculiar disadvantage in that the coercing signal amplitude must be readjusted for various control ratios. In the present arrangement the amplitude of the coercing signal of a single value is approximately optimum for all control ratios. This feature contributes to the practicability and desirability of the system when a single coerced tube is used for several control ratios merely by

changing the frequency constant of the LC circuit 13, by means of suitable switches and switching arrangements well known to the art. It may be pointed out that the coercion of circuits having a natural frequency higher than the coercing wave frequency and of course harmonically related is fairly simple but the coercion of circuits with frequencies which are integral multiples of the natural frequency of the coerced circuit has been very difficult prior to the present invention. See Proceedings of the I. R. E., page 1960, volume 18, No. 11, November 1930, paper by Groszkowski. This difficulty is not present in the operation of applicant's invention.

In order to enable resistor R to most efficiently achieve the above results, certain electrical conditions must be satisfied, one of which has already been hinted at. The resistance of resistor R must itself be as large as possible short of causing the circuit to stop oscillating. Of course, as has been stated before, circuit 13 must be tuned to the desired frequency which, however, must have a commensurable relation to the frequency of the coercing wave. In the most usual case, there is an integral harmonic relation and in general the smaller the harmonic the more easily coercible the oscillator becomes. The Q of this tuned circuit must always be the largest possible. This means practically that the ideal situation is where Q and the resistor R are both maximum. The usual limitation for the Q of said tuned circuit 13 is a practical one dependent on the design of the coil comprised in it. Since the limiting value of the resistance R is dependent on the maintaining of oscillations, said resistance cannot usually be made greater than about 10,000 ohms. The values of the tube potentials and the relations between such values, particularly the value of the bias of the control grid 5, which also should be as greatly negative as possible consistently with the ability of the circuit to maintain LC oscillations, do affect the degree of control but do not affect the optimum values, as above, of Q and the resistance in element R. Of course, the relations of the tube potentials must conform with the requirements for a negative transconductance tube oscillator. R must always be in the anode circuit in series with the LC circuit 13, although whether on the anode side or the battery side is immaterial, just so long as it is not bypassed to ground. The position shown is the desirable and the most practical one for other reasons of convenience in circuit layout. These considerations apply as well to other species of the invention as to the Fig. 1 species here being considered.

Fig. 2 represents a modified form of the invention otherwise represented by Fig. 1. The differences do not relate to the invention in any fundamental way. As a matter of fact these two figures actually indicate the evolution of the invention in applicant's mind. That is, Fig. 1 represents his earliest conception of it and Fig. 2 a later conception of it and a conception perhaps more mature and practical. For instance, the Fig. 2 circuit would tend to conform most nearly with modern practice of the invention and does represent very closely a practical embodiment of the invention found very effective in practice by applicant's assignee. Because the circuits are so nearly alike, duplicate reference characters have been used. The only change is the use of the synchronizing grid 9 to impress the coercing wave. That is, in Fig. 1

the coercing signal was impressed on one of the oscillator electrodes, grid 9 being deemed in that figure not to be an oscillator electrode and having an unimportant function and being connected directly to the cathode as in the case of a suppressor grid in a normally utilized pentode, whereas in the Fig. 2 circuit identically the same tube is used but this grid 9 has been separated from its direct connection to the cathode 6 and used to couple the coercing oscillator to the coerced oscillator. It should be noted that the resistor R, which is the principal novel feature of applicant's invention, is found in Fig. 2 in the same position as in Fig. 1. It has the same function in that circuit as in the first considered circuit and the considerations adduced in connection with the treatment of the Fig. 1 circuit, affecting said element R and associated elements, equally govern in the present instance.

Fig. 3 differs from Figs. 1 and 2 only as showing how the coercing wave may be introduced to the coerced oscillator by way of the control grid. Since this is the only distinctive feature and since the labelling is the same as in the other figures, further description is dispensed with.

The invention has been exemplified in three species in the specification above, but changes therefrom and other modifications representing new species may readily suggest themselves to those skilled in the art from a reading of this specification.

negative potential on said control grid, together with connecting circuits, the organization as a whole being adapted to constitute an oscillator of the negative transconductance tube type, said coerced oscillator being adapted to generate a wave having a frequency bearing an approximate commensurable relation to the frequency of the wave from the coercing oscillator, and means coupling said oscillators whereby said oscillators operate in locked frequency relation, said coerced oscillator also comprising a resistance in the anode lead, said resistance having the largest value and the bias on the control grid the largest negative value that the coerced oscillator will tolerate without cessation of sinusoidal oscillations while being coerced.

2. The organization specified in claim 1 including a capacitance coupling means between the anode and control grid, and a tuned circuit resonant at the desired coerced frequency in serial relation with said anode lead resistance between the anode and cathode, said coupling means between the coercing and coerced oscillators being adapted to connect said coercing oscillator between said cathode and anode.

3. The organization specified in claim 1, in which said negative transconductance tube oscillator also comprises an auxiliary grid interposed in the electron stream between the cathode 30 and anode, a capacitance means coupling the anode and control grid of the device, and a tuned circuit which is antiresonant at substantially the desired coerced frequency in series with said anode lead resistance between said anode and 35 said supply source, the Q of the tuned circuit having the greatest value consistent with the production and maintenance of stable oscillations of sinusoidal waves, and said coupling means between the coercing and coerced oscillators being adapted to connect said coercing oscillator between said cathode and auxiliary grid. 40
